[57] **CLAIM**

The ornamental design for a combination manipulator and intubator used in endoscopic surgery, as shown and described.

DESCRIPTION

FIG. 1 is a perspective view of a combination manipulator and intubator used in endoscopic surgery showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

FIG. 4.

FIG. 5.

FIG. 6.

FIG. 7.
